UNITED STATES PATENT OFFICE.

WALTER E. DAVIS, OF FITCHBURG, MASSACHUSETTS.

MAIL-BOX.

1,049,058.

Specification of Letters Patent.

Patented Dec. 31, 1912.

Application filed January 27, 1912. Serial No. 673,818.

To all whom it may concern:

Be it known that I, WALTER E. DAVIS, a citizen of the United States, residing at Fitchburg, in the county of Worcester and State of Massachusetts, have invented new and useful Improvements in Mail-Boxes, of which the following is a specification.

This invention is an improved mail box including an inclined bottom plate to discharge mail by gravity at one end of the box, a door at said end of the box hinged at its upper side, and also including a casing at one side of the box having a display opening and a movable indicating device in the casing, used for indicating the time when the next collection of mail is to be made from the letter box and arranged to be appropriately set when the door is opened, the invention consisting in the construction, combination and arrangement of devices, hereinafter described and claimed.

In the accompanying drawings:—Figure 1 is a side elevation of a letter box constructed in accordance with my invention, showing the door closed. Fig. 2 is a similar view of the same, partly in section, and showing the door open. Fig. 3 is an end elevation of the same. Fig. 4 is a horizontal sectional view of the same. Fig. 5 is a detail perspective view of the door.

The mail box 1, which may be of any suitable size and shape, and which may be made of any suitable material, is here shown as of an oblong rectangular form, provided with an inclined or pitched top or roof 2 and also with a socket 3 on one side whereby the mail box may be attached to a post or other support. An inclined bottom plate 4, which is preferably sheet metal, is arranged and secured in the lower side of the letter box and is adapted to discharge mail by gravity, at one end of the box through an opening 5. The said end of the box is also provided with an opening 6 through which mail may be placed in the box and there is a cover 7 for said opening, hinged at its upper side as at 8.

A door 9 is provided to close the opening 5 at the end of the box at which the inclined bottom plate discharges. This door is hinged at its upper side as at 10. At the vertical sides of the door are flanges 11 and 12 to partially overlap the vertical sides of the letter box and at the lower side of the door is a flange 13.

On one side of the box, near that end

thereof provided with the opening 5 is a casing 14 which forms a compartment which communicates with the interior of the box. This casing has a display opening 15 in its outer wall and is also provided with a display opening 16 in the said wall below the opening 15. The said display openings are glazed and in the opening 16 is a suitable slide 18 which is provided with a legend indicating when the last collection of mail was made from the box. In the casing 14 is mounted a revoluble indicating disk 19 the pivot of which is indicated at 20. This indicating disk is inscribed with legends or numbers indicating the times of various collections of mail from the box, as at 21, there being a slide inscribed with the legend such as "Next collection" indicated at 22, which is displayed also through the opening 15. One edge of the indicating disk 19 projects beyond that side of the casing 14 which is nearest the door 9, as indicated at 23, and the flange 12 of the door is recessed as at 24 to receive that end of the casing and cover the same and to also receive and to cover the projecting edge 23 of the indicating disk.

The door is provided with a suitable hasp 25 which, in connection with a staple 26 and a padlock 27 is employed for locking the door when the latter is closed. Any suitable means may, within the scope of my invention be employed for locking the door, and I do not desire to be limited in this particular.

When the door is closed, the edge 23 of the disk 19 is protected and said disk can not be casually turned. It is to be assumed that the disk at the last collection of mail was then set by the carrier to indicate the time of the next collection. When the door is opened, its lower side swings outwardly and upwardly from the opening 5 at one end of the mail box, and all the mail in the box is by gravity discharged by the inclined bottom plate 4, outwardly through the said opening, thus obviating the necessity of the carrier putting his hand in the box in order to draw out the mail. Having thus obtained the mail, the carrier before closing and relocking the door, places one finger on the projecting edge 23 of the display disk 19 and turns the latter a sufficient distance to cause an appropriate inscription indicating the next collection of mail to be displayed through the opening 15 as will be understood. Hence, anyone by glancing at

the mail box can not only ascertain the time of the last collection of mail from the slide displayed by the opening 16 but can also ascertain from that portion of the disk 19 which is displayed through the opening 15 the time when the next collection of mail will be made from the box.

While I have herein shown and described a preferred embodiment of my invention, I would have it understood that changes may be made in the form, construction and proportion of the several parts without departing from the spirit of my invention and within the scope of the appended claims.

15 I claim:—

1. A mail box having a door at one end provided with a flange which overlaps one side of the box when the door is closed, the said flange being provided with a recess and the box being further provided with a casing on the said side having a display opening and also having a slide opening at the end against which the flange of the door closes, a revolute indicating disk mounted

in the casing and projecting from the end 25 thereof next to the door, so that when the door is closed the flange closes against the end of the slide and the recess in the flange forms a housing for the projecting portion of the indicating disk.

2. A mail box having a door at one end provided with a flange which overlaps one side of the box when the door is closed, the said flange being provided with a recess, the box being further provided with a casing on the said side, having a display opening, and a revolute indicating disk mounted in the casing and projecting from the end 35 thereof next to the door so that when the door is closed the recess in the flange there- 40 of forms a housing for the projecting portion of the indicating disk.

In testimony whereof I affix my signature in presence of two witnesses.

WALTER E. DAVIS.
